UNITED STATES PATENT OFFICE.

RUDOLF WITTMANN, OF BROOKLYN, NEW YORK.

CYCLE.

SPECIFICATION forming part of Letters Patent No. 693,202, dated February 11, 1902.

Application filed March 29, 1900. Serial No. 10,690. (No model.)

To all whom it may concern:

Be it known that I, RUDOLF WITTMANN, a citizen of the United States, residing in Brooklyn borough, New York city, in the county of 5 Kings and State of New York, have invented new and useful Improvements in Cycles, of which the following is a specification.

By means of this invention a cycle-frame can be made simple and durable; and the invention resides in the novel features of construction set forth in the following specification and claims and illustrated in the annexed drawings, in which—

Figure 1 is a detail view of the headpiece. 15 Fig. 2 is a view at right angles to Fig. 1. Fig. 3 is a section along x x , Fig. 1. Fig. 4 is a section along y y , Fig. 3. Fig. 5 is a side elevation of a cycle-frame embodying my invention.

20 In the drawings is shown a cycle or vehicle frame of which the branch or section 1 is conveniently called the "top" branch and 2 the "front" branch. The intermediate section or seat-post branch is shown at 3, the rear branch or stays at 4, and the lower branch or bottom stays at 5. The rear branch is forked to straddle or extend at both sides of rear wheel 6. The section 4 is also formed of branches on each side of wheel 6, and these 25 sections 4 and 5 are secured or bolted to disks 8, as seen at 9, said disks forming a bearing for wheel 6 or for its axle or hub. The top flange of tube or bar 3 is shown at 10, and the lower end portions of the bars 2 and 3 at 30 section 5 are looped below this section, as seen at 14, to form a pedal or crank-hanger. This hanger or bearing 14 can be held closed by bolt or fastening 15.

The headpiece 16, with its ears or fastening 40 portions 17 and 18, is formed from a single piece of material. The lower tongue 18 is extended into tube 2 and secured by a suitable number of bolts or fastenings. Two bolts have been found to firmly connect the 45 front branch and headpiece. The top section 1 can be pivoted to or between the lug-sections 17, or the meeting portions of section 1 and attaching portion 17 can be formed angular, or, for example, square. This manner 50 of connection, as shown at 17, can be applied not only at frame part 1, but wherever required for connecting two pipes.

The headpiece 16 is shown with its center portion of contracted diameter as compared with the end portions, this construction having been found to give strength. A name or other device can be pressed directly into this headpiece. The edge portions of the headpiece are doubled or turned inward into the tube or body 16 and then flanged, as seen 55 at 20. The steering-post 21 extends through or swivels in the headpiece, and the flanges 20 can seat ball-races.

The connection 17 is readily made by bending parts of the tube 16 inward to form lips 65 17', Fig. 3, which are parallel if the frame part 1 is to swing or be adjustable or placed at an angle if the part 1 is to remain fixed. The frame part 1 can be secured by a bolt or fastening 34.

The steering-fork for the front wheel is simply formed of two sections, each section integrally comprising the lower or wheel-bearing part, the swiveling or intermediate part in headpiece 16 and forming the steering- 75 post, and the top or handle-bar-carrying part. The handle-bars 38 are shown each separately pivoted between the top parts of the fork, Fig. 1. The handle-bars have disk-shaped end portions seated between the fork-sections, a pivot 39 in the fork, and disks adjustably supporting the handle-bars, so that the latter can be set higher or lower. When set, a pin or fastening 40 passed through the fork and disks fixes the handle in the position 80 or adjustment required, the disks having a series of holes for the reception of pin 40, Fig. 2.

2. The steering-post parts of the fork-sections are concaved or formed into half-tubes, which when placed edge to edge can be clasped 90 or held by sleeve or tube 41, fitting into headpiece 16. The tube has a bent or flange part 42 and a collar 43, removably screwed or secured in place, and these parts 42 and 43, with the headpiece-flanges 20, form ball-races. 95 The sleeve 41 can be riveted or fastened to the steering-post or intermediate fork part.

What I claim as new, and desire to secure by Letters Patent, is—

1. A cycle-frame having a tubular seat-post frame and a front branch each having its lower end flattened into semicircular shape, the flat sides of said semicircular ends of the seat-post and front branch being arranged in 100

- juxtaposition and secured together, substantially as described.
2. A headpiece made of a single piece of metal bent into tubular form and having its edges doubled inward into the tube and flanged substantially as described.
3. A cycle-frame having its frame branches each formed from a single piece bolted directly to one another, the front and intermediate branches being bent to form a bearing or crank-hanger substantially as described.
4. A cycle-frame having its steering-fork formed of two sections of flat or sheet metal, each section integrally comprising the lower or wheel-bearing part, the swiveling or intermediate part and the top or handle-bar-carrying part, said lower part having its face or flat portion facing toward or in the plane of the wheel, its intermediate portion channelled
- or tube-shaped and its top part bent or placed out of the plane of the wheel-bearing part substantially as described.
5. A tubular connection 17 having lips bent into the interior thereof and a frame-piece 1 made to sit between the lips substantially as described.
6. A headpiece with a tubular lug having portions bent or lapped toward one another into the lug or tube to form a firm or rigid bolt-support at said lug substantially as described.

In testimony whereof I have hereunto set my hand in the presence of two subscribing witnesses.

RUDOLF WITTMANN.
